UNITED STATES PATENT OFFICE.

CARRIE P. MOORE, OF BON AIR, VIRGINIA.

DESIGN FOR A FLAG.

51,443.

Specification for Design.

Patented Oct. 30, 1917.

Application filed June 13, 1917. Serial No. 174,634. Term of patent 3½ years.

To all whom it may concern:

Be it known that I, CARRIE P. MOORE, a citizen of the United States, residing at Bon Air, in the county of Chesterfield and State of Virginia, have invented a new, original, and ornamental Design for Flags, of which the following is a specification, reference being had to the accompanying drawing, forming part hereof.

The figure is an elevation of a flag, showing my new design.

I claim:

The ornamental design for a flag, as shown.

CARRIE PICKETT MOORE.
